UNITED STATES PATENT OFFICE.

AMOS F. SEYMOURE, OF ALBION, INDIANA.

SCAFFOLD-BRACKET.

1,193,832.

Specification of Letters Patent. Patented Aug. 8, 1916.

Application filed April 22, 1916. Serial No. 93,004.

To all whom it may concern:

Be it known that I, AMOS F. SEYMOURE, a citizen of the United States, residing at Albion, in the county of Noble and State of Indiana, have invented certain new and useful Improvements in Scaffold-Brackets, of which the following is a specification, reference being had to the accompanying drawings.

10 This invention relates to certain improvements in scaffold brackets and it is an object of the invention to provide a device of this general character having novel and improved means whereby it may be applied in operative position with convenience and facility and whereby the plank supporting bars may be effectively maintained in varying positions.

15 The invention consists in the details of construction and in the combination and arrangement of the several parts of my improved bracket whereby certain important advantages are attained and the device is rendered simpler, less expensive and otherwise more convenient and advantageous for use, all as will be hereinafter more fully set forth.

20 The novel features of the invention will hereinafter be definitely claimed.

25 In order that my invention may be better understood, I will now proceed to describe the same with reference to the accompanying drawings, wherein—

Figure 1 is a view in perspective illustrating a scaffold constructed in accordance with an embodiment of my invention in applied position; Fig. 2 is a fragmentary view partly in elevation and partly in section illustrating the coaction between the brace bar and the locking member as herein embodied; and Fig. 3 is a fragmentary view partly in elevation and partly in section illustrating the lower end of the brace bar as herein embodied.

30 In practice it will be understood that a plurality of my improved brackets will be employed in connection with a scaffold, but for the purposes of disclosure I am describing and illustrating a single bracket.

35 As disclosed in the accompanying drawings, 1—1 denote supporting members comprised in my improved bracket, each of said members being preferably formed of flat metal having its lower portion 2 disposed on a predetermined lateral incline with its

lower extremity twisted, as at 3, to afford a mounting for the pivot member 4 herein disclosed as a conventional bolt with its coacting nut.

30 The upper end portion of each of the members 1 is provided with a pair of outstanding perforate ears 5 for a purpose to be hereinafter more particularly referred to, and said member 1 at a point above and below the pair of ears 5 is provided with a button-hole slot 6 with its restricted end portion extended upwardly. In practice, suitable headed members 7 may be adapted to be engaged with a wall W or the like and with which the members 1 are adapted to be detachably engaged through the medium of the button-hole slots 6 in a manner which is believed to be clearly apparent to those skilled in the art to which my present invention appertains.

35 Coacting with each pair of ears 5 is a plank supporting member 8 of predetermined dimensions and preferably T-shape in cross section with the head disposed upwardly and the web thereof extending between the ears 5 and pivotally engaged by the pivot member 9 disposed through the ears 5 and the web of the member 8.

40 The supporting members 8 are arranged in forward convergence and disposed through the outer extremities of said members 8 is the pivot member 10 which is also directed through the tail 11 of the locking member 12, said tail 11 being directed between the adjacent ends of the members 8.

45 Pivotally engaged with the pivot member 4 is the lower extremity of the brace bar 14 preferably T-shape in cross section and having its web extending between the bearings afforded by the twisted portions 3 of the members 1, and the inner and free longitudinal marginal portion of the web is provided with the longitudinally spaced shoulders 15 which are adapted to coact with the inner end of the opening 16 produced in the locking member 12, whereby the members 8 may be effectively held in a required adjustment. It will also be noted that the pivotal mounting of the locking member 12 permits the brace bar 14 to be freely disposed through the locking member and at the same time permits the requisite engagement of the locking member 12 with a shoulder 15.

50 While I have hereinbefore set forth my device as applied to a wall, it will be under-

stood that it can be mounted with equal facility upon a roof when the necessities of practice may so require.

For convenience in storing or transportation, the bracket may be folded into a compact bundle by simply raising the locking member 12 sufficiently to allow the supporting bar 14 to drop back between the two supporting members 1 and fold the supporting members 8 down upon the members 1. It is also to be observed in detail Fig. 3 that the inner lower corner of the brace bar 14 is square and sharp and when the device is in assembled position, will extend slightly beyond the rear edges of the members 1 to impinge the wall W or other support with which the bracket may coact, and whereby a further support for the load is afforded.

From the foregoing description, it is thought to be obvious that a bracket constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein

shown in carrying out my invention in practice.

I claim:

A scaffold bracket comprising two supporting members provided with anchoring means, plank supporting members pivotally engaged with the supporting members adjacent an upper end thereof, a brace bar ⁴⁰ T-shape in form and having its web disposed inwardly, the lower portion of the web being pivotally supported between the opposite extremities of the supporting members, a locking member pivotally engaged between ⁴⁵ the outer extremities of the supporting members and provided with an opening through which the brace bar is directed, said brace bar having the free longitudinal edge of the web provided with longitudinally spaced ⁵⁰ shoulders with which the inner end of the locking member is adapted to coact, the lower free corner of the web of the brace being sharp and adapted to extend beyond the rear edges of the first named supporting members when the plank supporting members are in extended position to afford a further support.

In testimony whereof I hereunto affix my signature in the presence of two witnesses. ⁶⁰

AMOS F. SEYMORE.

Witnesses:

MORTON P. THOMAS,
FRED B. MOORE.
